(57) **CLAIM**

The ornamental design for a marimba, as shown and described.

DESCRIPTION

FIG. 1 is a top perspective view of the marimba of the present invention;

FIG. 2 is a top view thereof;

FIG. 3 is a front view thereof;

FIG. 4 is an end view thereof;

FIG. 5 is another end view thereof; opposite of that shown in FIG. 4;

FIG. 6 is a rear view thereof; and,

FIG. 7 is a bottom view thereof.

The portions shown in broken lines are to illustrate environmental structure only, and form no part of the claimed design.
